COIN-CONTROLLED MECHANISM

Lincoln M. Keefe, Woodside, N. Y., assignor to
 Stewart Products Corporation, a corporation of
 Delaware

Application December 11, 1948, Serial No. 64,730

8 Claims. (Cl. 194—48)

1

This invention relates to improvements in coin controlled mechanisms and is directed more particularly to coin mechanisms actuated either by a coin or coins of one size, by a coin or coins of another size, by coins of still another size, or by combinations of coins.

One object of the invention is the provision of a coin mechanism having a plurality of actuatable elements each adapted to be actuated by the impact of a coin of a different value from the others by said coins as they are moving downwardly, said mechanism including a positionable member moved by said elements in accordance with the value of the coins actuating said elements. For example, the positionable member is moved one step by each nickel, two steps by each dime, and five steps by a quarter, whereby said positionable member, in fact, sets up credits in accordance with the values of one or a plurality of coins inserted in said mechanism.

A further object of the invention is the provision of a coin controlled mechanism which is formed mainly of metal stampings which may be comparatively thin (so far as thickness is concerned) and which may be made in widths commensurate with the strength necessary in the several parts thereof. This makes it possible to produce, in mass production, a precision mechanism of comparatively few parts which is light in weight, low in cost and each of which is a duplicate of the other.

A further object of the invention is the provision of a coin controlled mechanism in which the several elements which are actuated by coins of several values all incorporate ratchet means which define steps which finally result in the movement of a positionable member, suitable linkages between said elements and said positionable member being provided.

Another object of the invention is the provision, in a coin controlled mechanism, of a first element to be actuated by coins of one value, a second element to be actuated by coins of a different value, a third element to be actuated by coins of a still different value, a positionable member moved in accordance with the value of the total coins actuating either one or all of said members, a lever pivotally connected to the first and second of said elements through means linked to the third of said elements, the pivotal connection to said first mentioned element actuating as a pivot about which said lever moves in one direction upon the actuation of said second element, and the pivotal connection to said

2

second mentioned element acting as a pivot about which said lever moves in the opposite direction upon the actuation of said first element, and said lever remaining stationary when said third element is actuated, said positionable member moving in the same direction regardless of whether one, two or all of said elements is actuated.

A further object of the invention is the provision, in a coin controlled mechanism, of a plurality of elements each to be actuated by a coin of a different value, a positionable member moved by said elements, a distance proportionate to the total value of the coins entering said mechanism and actuating any or all of said elements, and a lever pivotally connected to all but one of said elements and pivotally connected to said positionable member through ratchet means forming a part of said one of said elements, none of said pivotal connections normally constituting a fulcrum until one of said elements pivotally connected to said lever is actuated by a coin, whereupon one of said pivotal connections, other than the one connected to the element actuated, becomes the fulcrum.

Yet another object of the invention is the provision, in a coin controlled mechanism, of a first element to be actuated by coins of one value, a second element to be actuated by coins of a multiple of said value, and a third element to be actuated by coins of a greater multiple of said value, said elements all being operatively connected to a common floating support, termed a positionable member, and escapement means associated with each of said elements and defining steps as follows: a first escapement means associated with said first element and defining steps each representing said one value, a second escapement means associated with said second element and defining steps which are multiples of the steps defined by said first escapement means, and a third escapement means associated with said third element and defining steps which are a greater multiple of the steps defined by said first escapement means, whereby said positionable member is moved through a series of steps representing the values of all of the coins which actuate said elements.

Other objects and advantages of the invention will be apparent to those skilled in the art from a study of this specification and the accompanying drawings.

Referring to the drawings, which illustrate by

way of example one embodiment of the invention:

Figure 1 is a side elevation of my new and improved coin controlled mechanism;

Figure 2 is a plan view of the mechanism taken along the lines 2—2 of Figure 1;

Figure 3 is an elevation of the mechanism shown in Figure 1, as seen from the opposite side thereof;

Figure 4 is a fragmentary view of the coin controlled mechanism, such as that shown in Figure 3, operatively connected to a differential mechanism, said differential mechanism being shown partly in section;

Figure 5 is an end elevation of said differential mechanism operatively connected to the positionable members of two coin controlled devices, such as the one shown in Figures 1, 2 and 3;

Figure 6 is a side elevation partly broken away showing a coin tester and scavenger positioned to deliver coins to coin controlled mechanism, such as that shown in Figures 1, 2 and 3, and coin dumping means adapted to return coins from said coin controlled mechanism to the purchaser when the coin return button is depressed and adapted to dump the money through a separate channel when the money is accepted by any mechanism with which said coin controlled mechanism is associated;

Figure 7 is an end elevation of the coin tester and scavenger shown in Figure 6 and having associated therewith a coin chute for delivering coins to the coin controlled mechanism;

Figure 8 is a plan view of the coin return mechanism as seen along the lines 8—8 of Figure 6;

Figure 9 is an elevation showing the positions of the coin return mechanism when the coin return button is depressed;

Figure 10 is a perspective view showing a price bar operatively connected to the differential mechanism shown in Figures 4 and 5, and showing a lock-out chain paralleling said price bar and showing elements movable with a push button for engaging said price bar and said lock-out chain;

Figure 11 is a sectional elevation showing a push button and its relation to the price bar, the lock-out chain and mechanism for ejecting articles from an article column;

Figure 12 is similar to Figure 11 except that it shows the ejector means ejecting an article;

Figure 13 is an elevation of linkages between the ejector means of Figure 11, a one revolution clutch and motor control means set by one of the push buttons, such as that shown in Figure 11;

Figure 14 is a plan view of a portion of Figure 13 seen along the lines 14—14 thereof;

Figure 15 is a sectional view taken along the lines 15—15 of Figure 4; and

Figure 16 shows a group of key plates representing different prices from five cents to twenty-five cents so that a comparison of them may be made.

Referring first to Figures 1, 2 and 3, which illustrate the coin controlled mechanism, a main plate 40 forms a support for the elements, some of them being positioned on one side of the plate, some of them on the other side of the plate, and some of them extending from one side of the plate to the other through openings formed therein, as will hereinafter be explained. Secured to the plate 40 on one side thereof is a U-shaped channel 41 having a passage 42 therein for quarters. This channel has flanges 43 and 44 formed on the opposite edges thereof and these flanges are spot

welded to the plate 40 as at 45. The flange 43 terminates a substantial distance from the lower edge 46 of the plate 40, leaving an edge opening 47 communicating with the interior of the channel. The channel 41 has several elongated perforations, such as the perforation 48, formed therein, and on the lower end the channel has an ear 49 which is secured to the plate 40 at the point 50 with a suitable spacer therebetween. The flange 44 terminates a substantial distance from the lower edge 46 of the plate and an opening or slot 51 communicates with the interior of the channel in the same manner as it does in the channel 41.

A shouldered screw 52 has journaled thereon a lug 53 and on the outer end of this lug is secured a rod 54 which has an upturned portion 55 on its right end. This rod, as may be seen in Figure 1, is inclined to the horizontal and has a horizontal portion 56 which extends through the slot 51 into the interior of the channel 41 so as to be engaged by twenty-five cent coins passing down the channel 41. A spring 57 has its lower end secured to the rod 54 and has its upper end engaging a stud 58. A stud 59 mounted in the plate 40 serves as a stop to limit the upward movement of the rod 54 and the rod is urged against said stop by means of the spring 57. An arm 60 has its left end, as seen in Figure 1, journaled on a stud 61 mounted in the plate 40, and has its right end extending beyond the right edge of the plate 40 and carrying a stud 62. This stud constitutes what is termed "a positionable member." A bracket member 63 has offset lugs on each end which are secured to the plate 40 by means of spot welds 64, or in any other suitable manner and the portion between the offset lugs is parallel to and spaced apart from the plate 40 and forms a guide for the arm 60.

A lever member 65 has its upper end journaled on a stud 66 which is mounted in the arm 60. The lever member has an upper portion 67 of substantial width and a lower portion 68 which is substantially narrower than the portion 67, and a lower end portion 69 which is narrower than the portion 68, the left edges of the portions 68 and 69 having a curved surface 70 therebetween. A right angled bracket 71 has a vertical portion which is secured to the plate 40 by means of spot welds 72 and has a horizontal portion 73 which has an elongated slot formed therein through which the lower end 69 of the lever member 65 extends. The upper portion 67 of the lever member has an elongated hole 74 formed therein to lighten it, and below this hole is formed a ratchet slot 75 which is in effect a follow cam having lands 76 and 77 formed therein. The lever member 65 has a stud 78 mounted thereon to which one end of a spring 79 is secured.

A lever 80 carries on its right end, as seen in Figure 1, a stud 81 which extends into the ratchet slot 75 and which normally engages the land 76. The lever 80 intermediate the ends thereof has a stud 82 upon which is journaled the lower end of a lever 83. The spring 79 described above has its other end connected to the stud 82 and thus the lever member 65 is urged in a clockwise direction about its pivot 66 and thereby the land 76 is normally maintained in engagement with the stud 81, and when the lower end 69 of the lever member 65 is displaced by the end 55 of the rod 54, the stud 81 engages the land 77, thus the stud 81 and the ratchet slot 75 constitute an escapement. The stud 82, in addition to having an upstanding portion upon which the lever 83 is journaled, has

an extension 82a which extends through an arcuate slot 84 formed in the plate 40. The plate 40 has a rectangular hole 85 formed therein through which the lever 83 extends. The lever 83 has an offset portion 86 which extends through the hole 85, and it has a vertical portion 87 on the side of the plate 40, as seen in Figure 1, and a second vertical portion 88 on the side of the plate, as seen in Figure 3. The upper end of the portion 88 is journaled on a stud 89 carried by a lever 90 on the opposite face of the plate 40. The lever 90 has one end journaled on a stud 91 mounted in the plate 40. A stud 92 is carried by the other end of the lever 90 and has journaled thereon the upper end of a lever member 95.

The lever member 95 extends generally downwardly on the face of the plate, as seen in Figure 3. Secured to the plate 40 is a bracket having a vertical portion 93 which is secured to the plate in any suitable manner, for example, by spot welds 94 and this bracket has a horizontal portion 96 which has a slot formed therein in which the lower end of the lever member 95 forms a working fit.

A plate member 97 is journaled on a stud 98 on the plate 40 and it has an upturned ear 99 to which one end of a spring 100 is secured. The other end of this spring is secured to the horizontal portion 96 of the bracket. The plate member 97 has a lug portion 101 to which is secured a rod 102. A stud 103 mounted in the plate 40 forms a stop against which the rod 102 is normally held under the urge of the spring 100. The plate member 97 also has an upturned lug 104 which is positioned in a ratchet groove 105 formed in the lever member 95. This ratchet groove has lands 106, 107, 108 and 109 formed therein with which the lug 104 cooperates. Normally the lug 104 is in engagement with the land 106 and it engages the other lands in accordance with the number of dimes passing through the coin passage 111. A plate 110 is supported in spaced relation to the plate 40 and this plate and its supports form a coin passage 111 to receive dimes. The end 112 of the rod 102 extends into the passage 111 so as to be actuated by the impact of coins moving downwardly in the passage 111. A bracket has a vertical portion 113 which is spot welded or otherwise secured to the plate 40. This bracket has a horizontal portion 114 which has formed therein a guide slot. A lever member 115 has its lower end journaled on a stud 116 carried on the left end of the lever 80 (as seen in Figure 1).

The lever member 115 has a portion 117 which is on the side of the plate shown in Figure 1, an angular portion 118 which extends through a hole 119 formed in the plate 40, and a vertical portion 120 which extends upwardly on the face of the plate 40, as seen in Figure 3. The upper end of the lever member 115 extends through the slot above described as formed in the horizontal portion 114 of the bracket. Thereby the upper end of the lever member 115 is guided by this bracket. The portion 117 of this lever has a stud 121 mounted thereon and a spring 122 has one end connected to the stud 121, and the other end is connected to the stud 82 on the lever 80 so that this spring urges the lever member 115 in a clockwise direction, as viewed in Figure 1, which is a counterclockwise direction, as viewed in Figure 3. A series of notches 123 is formed in the lever member 115 and these notches are urged by the spring 122 into engagement with the left edge of the slot formed in the bracket, as viewed in

Figure 3 and thereby the notches and said edge of the slot cooperate to form an escapement.

A stud 124 has journaled thereon a plate member 125 which has an upstanding lug 126, which is adapted to engage the upper end of the lever member 115 and moves the same in a clockwise direction, as viewed in Figure 3, so as to disengage one of the notches 123 from the bracket portion 114. The plate member 125 has a downwardly projecting portion 127 to which a rod 128 is secured. The rod 128 has a portion 129 which extends vertically downwardly and formed integral with this portion is an angular portion 130.

15 A spring 131 has one end secured to the plate member 125 and the other end secured to a stud 132 mounted on the plate 40. The spring 131 connects to the plate member above its pivot, and consequently the rod 128 is urged in a counterclockwise direction and the lower end rests against a spacer member 133.

20 A channel 134 has flanges 135 and 136. The flange 135 is secured to the plate 40 by spot welds 137, for example, and the flange 136 is secured to the plate 40 by means of screws 138 extending through the spacer 133, plate 110 and its spacer, thereby providing between the channel 134 and the plate 110 a passage 139 for nickels. Since the angular portion 130 of the rod 128 extends into the passage 139 it is actuated by the impact of nickels passing through the passage 139.

25 A plate 40 has spaced mounting holes 140 and 141 adapted to engage supports in a machine in which the coin controlled mechanism is to be mounted. Spaced apart from the holes 140 and 141 is a hole 142 adapted to engage a shouldered stud in a machine in which the plate 40 is to be mounted so that the plate may be secured thereto by means of a screw and washer (not shown).

30 Referring to Figures 4, 5 and 10, two coin controlled mechanisms, such as that shown in Figures 1, 2 and 3, are employed, and the positionable member 62 of one of them is pivotally connected to a link 143. The link 143 has a struck out tongue 144 to which the lower end of a spring 145 is connected. The upper end of the spring is connected to a hook 146 formed on a lug 147 which engages a groove formed in the stud 62. A bar 148 has a lug 149 secured to the upper end thereof which has a hole 150 formed therein, and a boss 151 carried by the link 143 forms a working fit in the hole 150 and is retained therein by a clip member 152. The bar 148 has a rack 155 formed therein and this rack is reciprocally carried in a channel 154, which is in turn mounted in a U-shaped channel 153.

35 The positionable member 62a on a second coin controlled mechanism, like the one shown in Figures 1, 2 and 3, has a link 143a the upper end of which has a hole therein journaled on the stud 62a and retained thereon by means of a clip 147a having its lower end in the form of a hook 146a. The link 143a has an ear 144a, and the spring 145a has its upper end connected to the hook 146a and its lower end connected to the ear 144a. Thus the clip 147a is maintained in engagement with a groove formed in the stud 62a.

40 A bar 148a has a lug 149a secured to the upper end thereof, which has a hole like the hole 150 formed therein and a boss 151a carried by the link 143a forms a working fit with said hole and is retained by a clip member 152a. The bar 148a has a rack 155a formed therein and this rack is reciprocally carried in a channel 156 which is in turn mounted in a U-shaped channel 153 so that

the channels 154 and 156 have their open ends facing each other.

A metallic block member 157, which due to its mass constitutes a weight, is reciprocally carried in the channel 153 and it carries a stud 158 upon which a pinion 160 is journaled. This pinion meshes with both the rack 155 and the rack 155a. The stud 158 has a groove formed therein which is engaged by a clip 159. The clip 159 has its lower end in the form of a wide hook 161 to which the upper ends of springs 162 and 163 are secured.

A connecting rod generally designated by the numeral 165 has an elongated slot 166 formed in the upper end thereof which slidably engages the stud 158 and which is located fore-and-aft between the clip 159 and a hub 167 on the pinion 160. The connecting rod 165 has near the other end a horizontal portion 168 which joins an end portion 169 which is parallel to the main body of the connecting rod 165. The horizontal portion 168 has holes in opposite edges which are engaged by the lower ends of the springs 162 and 163 so that the connecting rod 165 is urged upwardly by the springs 162 and 163, and thereby the lower end of the elongated slot 166 is maintained in engagement with the stud 158. The channel member 153 has secured thereto, for example, by spot welding a bracket member 170 which may be secured to a supporting part 171 of the machine in which it is mounted by means of screws 172.

A crank member 175 is journaled on a stud 176 and carries a stud 177 upon which a hole formed in the lower end 169 of the connecting rod 165 is journaled. The crank member has a radial slot 173 formed therein; and a bar 174, reciprocally mounted in the frame of the machine and constituting what might be termed a price bar, extends across all of the columns of the machine. This bar is moved in steps and its position represents a credit set up in the machine as a result of all of the coins entered into either one or both of the coin controlled mechanisms, as will hereinafter be more fully explained.

The bar 174 carries a stud 178 which engages and forms a working fit with the radial slot 173. The crank member 175 has a hub 179, and the stud 176 is secured to an extension 171a of the frame 171.

The block member 157 has secured thereto a depending arm 180 which has an offset portion 181 formed integral therewith, the purpose of which will be presently described. The frame member has a plurality of stepped rectangular perforations 182 formed therein, and these form clearance holes for the push buttons for the several columns of the machine which are disposed in a row adjacent to the price bar 174.

Referring now to Figures 6, 7, 8 and 9, a scavenger and coin tester 183 is positioned above one of the coin controlled mechanisms 40 and the second coin tester and scavenger 183a is positioned above the coin controlled mechanism 40a. The scavengers and testers are supported on a bracket 184, for example, by means of screws 185, and positioned below the left hand sides of these testers and scavengers is a receptacle 186 which receives the coins rejected by both of the scavengers and testers. The receptacle 186 tapers downwardly so that the bottom edge 186a is inclined substantially for the purpose of delivering such coins to a chute 187 via which the coins are returned to the purchaser. The side walls 188 of the receptacle 186 have vertical corrugations 189 formed therein to encourage the coins to keep

rolling, thereby preventing them from becoming lodged in the receptacle.

The bracket 184 in which the scavengers and testers 183 and 183a are mounted has secured thereto by means of screws 191 a lever 190, and the bracket 184 is adjustably supported on a frame in the vending machine so that the bracket 184 may be leveled independently of the rest of the machine, regardless of how the floors slant in any building in which the machine is located. For adjusting the level of the bracket 184 screws, such as the screw 192, for example, are provided.

Between the coin scavengers and coin testers and the coin controlled mechanisms 40 and 40a are positioned members, such as the member 193, which include coin passages for the several sizes of coins. For example, in the arrangements shown in the drawings the twenty-five cent coins are delivered to the coin chute 41 on the coin controlled device, the dimes are delivered to the coin passages 111 in the coin controlled mechanism, and the nickels are delivered to the chute 139. The member 193 is secured to the coin controlled mechanism 40a, for example, by means of screws 194.

A stud 195 on the frame carries a bell crank 196 which has an arm 197 carrying a stud 198 upon which is journaled a bearing hole formed in the lower end of the connecting rod 199. This connecting rod extends upwardly and its upper end is journaled on a stud 200 carried by a lever 201 which is journaled on a shaft 202 carried in a bracket 203, which is secured to a frame member 204. The lever 201 carries a stud 205 on its outer end upon which is journaled a roller 206. The lever 201 is fixedly connected to a second like lever 207 which carries a stud 208 upon which a roller 209 is journaled. When the coin return is operated by the purchaser, to get his money back, as will presently be described, the connecting rod 199 is moved downwardly causing the rollers 206 and 209 to move downwardly and actuate the scavenger-testers 183a and 183 respectively to cause them to eject into the receptacle 186 any coins or the like remaining therein.

The bell crank 196 has an arm 210 the outer end of which carries an engaging member 211 which engages the end 181 of the depending arm 180 for raising the metallic block 157 of the differential and thereby effecting the resetting of both the coin controlled mechanisms 40 and 40a. The bell crank 196 has an arm 212 extending upwardly, the upper end 213 of which is reduced in dimension and engages a slot 214 formed in a sliding member 215. The sliding member has an upturned end 216 which is adapted to be engaged by a coin return button 217 reciprocally carried in a front frame member 218, a spring 219 being provided for returning the coin return button 217 to its normal position each time it is depressed and released. A frame member 220 has a guide slot 221 formed therein and a stud 222 carried by the sliding member 215 extends through this slot and is guided thereby. A frame extension 223 has a rectangular slot 224 formed therein through which the sliding member 215 extends and with which it forms a working fit.

Spaced apart axially on the stud 195 and movable with the bell crank 196 is an arm 225 which carries a stud 226 upon which is pivotally mounted a member 227. The member 227 has an arm 228 which has an angular end portion 229 which is adapted to engage the notched end 230 of a lever 231. The member 227 also has an arm 235

the outer end 236 of which is curved somewhat in the form of a hook. Cooperating with the arm 235 is a roller 237 which is journaled on a stud 238.

The lever 231 is journaled on a stud 232 and has a tail portion 233 which cooperates with a stud 234. A lug 239 formed on the member 227 has a hole therein to which one end of a spring 240 is attached. The other end of this spring is attached to a stud 241 on the plate of the coin control 40a so that the spring tends to urge the member 227 in a counterclockwise direction about the pivot 226.

The member 227 has a curved arm 242 formed integral therewith which carries on its outer end an engaging member 243 which is adapted to engage and depress an extension 244 formed on a shaft 245, as may be best seen in Figure 8. The shaft 245 has its left end 246, as seen in Figure 8, angular with respect to the main portion of the shaft, and between the end 246 and the extension 244 the shaft 245 is journaled in a hole formed in the frame extension 223 which is secured to a frame member 248. A bracket member 249 secured to the frame member 248 has extending into it from the bottom end thereof a V-shaped notch 250. The shaft 245, Figure 9, is urged into working engagement with the apex of the V-shaped notch 250 by means of springs 251 and 252, having their lower ends secured to a shaft 253. The other ends of the springs 251 and 252 are secured to a bracket 254, as may best be seen in Figure 6.

A coin basket 255 is secured on the frame in fixed relation to the coin controlled mechanism 40 and 40a. This basket is generally in the form of a hollow inverted frustum and the lower end thereof is open and provided with a closure member 256 having side flanges 257 and 258. The closure member 256 is secured on the flattened end 259 of the shaft 245 by spot welding or any other suitable means. The function of the shaft 245 and the closure member 256 is two-fold. When the coin return button 217 is depressed the shaft and the closure member 259 thereon are rotated in a counterclockwise direction, as viewed from the left side of Figure 6, so that the coins in the basket 255 are discharged into a passage (not shown) which leads to the article delivery receptacle (not shown). The other function is effective when the machine is operated to deliver an article, and during the delivery of the article the shaft and the closure member 256 are rotated in a clockwise direction, as viewed from the left side of Figure 6, thereby dumping the coins into a passage which leads to an accepted coin receptacle (not shown) in the base of the machine.

Operation of the coin controlled mechanisms

Since the coin control is dual, and due to the differential arrangement between them and the price bar 174, all of the coins involved in the transaction may be inserted in either one of the coin controls 40 or 40a, or some of the money can be placed in one and some in the other. For example, if twenty-five cents is to be put into the machine and this is in change, twenty cents could be put into one of the coin controls and five cents in the other, or fifteen cents in one and ten cents in the other.

When a coin, for example a nickel, is placed in one of the coin controls, for example the coin control 40, it passes down the passage 139 (Figure 3) and by impact against the end 130 of the rod 128 causes the lever to move in a clockwise direc-

tion on the axis 124, thereby disengaging one of the notches 123 from the bracket portion 114. Now since the lever member 115 is fulcrumed at 116 to the lever 80 and since the lever 80 is fulcrumed at an intermediate point at 82, this upward motion of the lever member 115 is changed to a downward motion of the other arm 60 by the lever 80, and this is imparted to the arm 60 via the arm 65, thereby causing the stud 62 to move downwardly an increment of movement representing five cents. This movement may be imparted directly to the price bar 174 by any common form of linkage. However, in the embodiment shown, where two coin controls are employed, the studs 62 move differential mechanism, such as that shown in Figures 4 and 5, the operation of which will be presently described.

It will be understood that if two nickels pass through the passage 139 the lever member 115 is moved upwardly twice for a sum of two notches, or if more nickels are passed through the passage 139 the lever member 115 is moved upwardly a corresponding number of notches.

Now suppose a dime is inserted via the passage 111: It strikes the end of the rod 102, thereby moving it in a clockwise direction about its fulcrum 98. As this occurs the lug 104 in the ratchet groove 105 on the lever member 95 is also swung in a clockwise direction and disengaged from the land 106. This causes the lever member 95 to move downwardly, and as the spring 100 urges the lug 104 in a counterclockwise direction it is immediately pulled into position to arrest the land 107, with the result that the lever 95 is moved down from the land 106 to the land 107. This lever through the pivotal connection 92 causes the lever 90 to move in a counter-clockwise direction about the fulcrum 91.

Now the lever 90 through the lever 83, which is fulcrumed thereto at 89, causes the lever 80 to swing in a counter-clockwise direction about the fulcrum 116, and the movement is thence imparted to the lever 60 via the lever member 65 in the same manner as described above for the nickel. It will be noted that when the control is actuated by a nickel the lever 80 is fulcrumed at 82, whereas when the control is actuated by a dime the lever 80 is fulcrumed about the fulcrum 116. In the case of the dime the lever 80 is fulcrumed about 116, and consequently its opposite end moves twice as far (a space equal to two five cent increments), and this motion of course is transmitted to the arm 60 via the lever member 65.

If two dimes are sent down the passage 111 the first one causes the lever member 95 to move downwardly from the land 106 to the land 107, as just described. When the second dime is inserted it causes the lever member 95 to move downwardly from a point where the land 107 is engaged by the lug 104 to a point where the land 108 engages it. A third dime would cause the lever member 95 to move still further downward to a point where the land 109 engages the lug 104.

When a quarter is passed through the passage 41 it engages the end 56 of the rod 54 and by impact causes the lug 53 to swing in a counter-clockwise direction about the fulcrum 52, with the result that the up-turned portion 55 thereon acts against the curved surface 70 on the lower portion 68 of the lever member 65, thereby causing the lever member 65 to swing in a counter-clockwise direction (Figure 1) about the fulcrum 66. This causes the land 76 to become disengaged from the stud 81 and allows the lever

member 65 to move downwardly until the land 77 thereon engages the stud 81 and is arrested by it. The spacing of the lands 76 and 77 is such that the stud 62 carried in the lever 60 moves down a distance equal to five of the nickel increments.

From the above description it will be evident that nickels alone, dimes alone, quarters alone, or combinations thereof, will actuate the coin control and that the movement of the lever 60 carrying the stud 62 will be in increments (each of which is equal to the length of movement representing a nickel) depending on the amount of money inserted.

Now where two such coin controls are employed, the arrangement is shown in Figures 4 and 5. Linked to the lever 60 through the medium of the stud 62 is a rack 148 having teeth 155. Linked to the second coin control lever is a similar rack 148a which has teeth 155a. Now the teeth of these racks face each other, and between them and meshing with both of them is a pinion 160 which is carried on a slidable block 157 which also constitutes a weight.

Now referring to Figure 5, if coins are inserted in the left hand coin control the rack 155 is moved downwardly thereby, and since the rack 155a is immobile the pinion rolls along the teeth 155a and also moves downwardly. Through the link 168 the crank member 175 is moved on its fulcrum 176, thereby causing the price bar 174 to move.

If the coins are inserted in the right hand coin control the rack 155 connected to the left hand coin control remains stationary, and the teeth of the pinion 160 roll along the teeth 155 as the rack 148a moves downwardly, and through the medium of the link 168 the crank 175 is rotated.

If some of the coins are inserted in one coin control and some in the other, each coin individually effects a downward movement of the pinion 160, the link 168 and a rotation of the crank 175.

From the above it will be quite evident that the coins may be inserted in either one of the coin controls or that some of them may be inserted in one coin control and some in the other, and the same effective result would be obtained in either case.

At the end of a vending operation the depending arm 180 is raised upwardly during the resetting operation, and thereby the weight member 157 and the pinion 160 are elevated to their normal positions.

Referring to Figure 6, it will be noted that the depending arm 180 and its offset portion 181 are in cooperative relation with the horizontal extension 272 of the arm 271, as hereinafter described in connection with Figure 6.

Other features of the machine

The machine has a main shaft 260 which is rotated through an arc and returned to its normal position during each operating cycle by means of mechanism shown in Figure 13 and which will presently be described. Fixed on the shaft 260 is a lever 261 which has an engaging surface 262 which engages the right angled portion 246 of the shaft 245 and moves the shaft 245 and the member 256 in a clockwise direction, as viewed from the left side of Figures 6, 8 or 9, thereby causing coins from the basket 255 to be delivered to the accepted receptacle. The lever 261 has a lug 263 thereon to one end of which a spring 264 is secured.

A bell crank 265 has a depending arm 266 with a hole 267 adjacent to the end thereof. One end of a spring 268 engages the hole 267 and the other end of the spring is secured to a fixed boss 269 on the frame of the machine. The arm 266 has an ear 270 formed integral therewith and the other end of the spring 264 engages this ear and urges the bell crank 265 to a point where its other arm 271 normally abuts the lug 263. The arm 271 has a horizontal extension 272 which engages the depending arm 180 and resets the differential, the two coin controlled mechanisms 40 and 40a connected thereto, and the price bar 174. When the machine is operated to deliver an article the shaft 260 moves first in a clockwise direction, as viewed from the end seen in Figure 6, and consequently the arm 261 and the bell crank 265 move therewith because the arm 261 is keyed on the shaft 260 and the bell crank 265 is held against the lug 263 by the spring 264 and this movement is abetted by the spring 268. As the shaft is rotated in a clockwise direction, as stated above, the surface 262 engages the angular end 246 of the shaft 245 and causes the acceptance of the coins. Since the bell crank 265 is following the movement of the arm 261, the extension 272 on its arm 271 engages the depending member 180 and resets the mechanisms and the price bar, and it does it under the urge of the spring 268 and the urge of the spring 264 because by this time the arm 261 has advanced to a stage where the lug 263 has moved out of contact with the arm 271 in effecting the delivery of the article. After the delivery of the article the shaft 260 rotates through an arc in a counterclockwise direction, as viewed from the end shown in Figure 6, and the arm 261 and the bell crank 265 are returned to their normal positions which are the positions shown in Figure 6.

Referring now to Figure 10, the differential mechanism is shown partly broken away, and the connections to the price bar 174 are shown. The price bar 174 has a series of notches 273, 274, 275 and 276 formed therein. These notches are engaged by key plates such as the key plate 277 carried on the selector push buttons such as push button 278 shown in Figure 11. Parallelizing the price bar 174 is a lock-out chain generally designated by the numeral 280. This chain has a confined space between two end barriers 279 and 281 with which aligned slots 282, 283, 284, 285 communicate. These slots are formed in side walls 286 and 287, which also form guides for a series of slidable members 288, 289, 290, 291, 292 and 293. Each of these slidable members has a bevel 294 formed at one end thereof and a bevel 295 formed at the other end, so that when they are placed in an area within the space between the side walls 286 and 287 and the end barriers 279 and 281, the beveled surfaces 294 and 295 match beveled surfaces 296 and 297 on a plunger 298 which is also mounted on the push button 278 and which is movable therewith.

When the push button 278 is depressed or pushed in the beveled end 296, 297 engages one or the other or both of the beveled surfaces 294 and 295, forms an entering wedge and enters between the adjacent ends of any two of the movable members 290 to 293. In Figure 10 this plunger is shown positioned between the slidable members 290 and 291, and when the plunger is so positioned all of the space between the barriers 279 and 281 is occupied by the several

13

slidable members and the plunger, and therefore no other plunger on any other push button in the machine can enter between the other movable members of the chain after a first one has entered.

The lock out chain 290 is shown in Figure 11 as positioned on a bracket 299 secured to the frame member 171a. The price bar 174 is slidably mounted in a bracket 300 which is also secured to the frame member 171a. The bracket 300 has perforations or openings 301 formed therein in alignment with the key plates 277 carried by the push buttons 278, so that said plates may pass through the same and engage one of the notches formed in the price bar 174. The plates 277 have forms which may be compared by referring to Figure 16. The key plate 277a has a tab extension 400 which is tangent to one edge thereof and spaced apart from the other edge. When the tangent edge is on the right this key plate represents five cents; when it is turned over so that the tangent edge is on the left it represents twenty-five cents. The key plate 277b has a tab extension 400a the same width as the tab 400 by being notched out at 401 extending in from one edge and at 402 extending in from the other edge. When the key plate is positioned with the narrow notch to the right it represents ten cents, and when it is placed with the narrow edge to the left it represents twenty cents. The key plate 277a has equal notches 403 formed therein from each edge thereof, leaving a tab 400b centrally located thereon and this key plate represents fifteen cents.

The push button is slidably mounted in a socket 302 which extends through an opening formed in the frame 171a and which is secured thereto by means of escutcheon pins 303. The main shaft 260 has secured thereto by means of a rivet 304 a metallic stamping having a portion 305 which partially embraces the shaft 260, having an extension 306 the front portion 307 of which is in the form of a curved plate. Coextensive with the portion of the extension 306 is a bracing plate 308. A second bracing member 309 formed integral with the portion 305 has its extremity 310 in contact with the extension 306 in an area spaced apart from the bracing means 308. Opposite the extremity 310 is a bracket member 311 and this bracket member and the extremity 310 may be spot welded to the extension 306. The curved portion 307 has a rectangular opening 312 formed therein which is adapted to be engaged, during a delivery operation, by a hook 313 formed on the end of an arm 314.

A rectangular plate member 315 has upturned edges and channels parallel to the edges (not shown) between which the arm 314 is pivoted. Secured to the arm 314 is a hub member 316 which is journaled on a shaft 317 carried in the rectangular member 315. The rectangular member has secured to its lower end a pair of spaced arms one of which is designated by the numeral 318 and these arms have their extremities embracing and journaled on the main shaft 260 so that they are freely movable thereon. The member 315 also carries a tab 319 which forms a stop against which the arm 314 may normally rest. Extending downwardly from the hub 316 is a curved tail 320 which is actuated by the angular tip 321 of a bar 322 which forms an integral part of the push button 278. Extending from the upper end of the plate 315 is a pair of curved brackets one of which is designated by the numeral 323 and secured to these brackets is a curved plate

14

324 which preferably has its engaging end 325 serrated.

Extending all the way across the machine beneath the push buttons is a rock shaft 326 which has an embracing member 327 thereon. This embracing member has an extension 328 which is angular with respect to the vertical when the shaft 326 is in its normal position and which is moved from its normal position by means of a screw head 329 carried on the bottom edge of the push button assembly.

Secured on the outer end of the shaft 326, as may be seen in Figure 13, is a bell crank 330 which has an arm 331 with an upturned tab 332 formed thereon to which one end of a spring 333 is secured. The other end of the spring 333 is connected to a stationary post 334. The bell crank 330 has an arm 335 which carries a stud 336. Journaled on this stud is a bearing hole formed in one end of a bar 338 and this bar is retained on the stud 336 by means of a spring clip 339.

Returning to Figure 11, the machine has a second shaft 340 which is embraced by member 341 having its extremities abutting each other to form a continuous radial arm 342. The arms 318 shown in their normal positions in Figure 11 are urged to this normal position by means of springs 343 secured to the arms and to the frame member 171a. Carried on the outer end of the shaft 340, as may be seen in Figure 13, is a crank 344 which has an end 345 bent at right angles to the main body of the crank and this comes to rest against a member to be presently described. The crank 344 has an ear 346 with a hole through which is engaged by one end of a spring 347. The other end of this spring is connected to a fixed post 348 so that the spring continuously urges the crank 344 and consequently the shaft 340 and the radial arm 342 thereon to their normal positions.

Referring again to Figure 11, since the crank just described maintains the shaft 340 and the radial arm carried thereby to the position shown in Figure 11, it can be seen that when the push button 278 is depressed the end 321 of the member 322 which forms an integral part of the push button engages the curved tail 320 and swings the arm 314 upwardly so that the hook end 313 thereof enters the opening 312 and engages the curved member 307, so that when the shaft 260 is rocked in a counterclockwise direction, as seen in Figure 11, to deliver an article and rocked in a clockwise direction to again assume its normal position, the article ejector 324 moves therewith and ejects the article.

Figure 12 shows the shaft 260 swung almost its entire stroke in the counterclockwise direction, thereby ejecting an article 349 from the article column 350. As the article delivery stroke is completed and the mechanism is returned to its normal position the crank 344 is moved through an arc in a counterclockwise direction with the result that the end 321 which, during the delivery and return operation, was engaged by the ends of the arm 342, is released from these ends due to said arcuate movement of the shaft 340. As soon as the end 321 is released the push button returns to its normal position, which is the position shown in Figure 11.

Referring again to Figure 13, the bar 338 reciprocates in a suitable slot 351a formed in a plate 351. The bar 338 near the lower end thereof has preferably formed integral therewith a lateral tab 338a which extends beyond the end 352 of the bar 338 so that the end 352 constitutes an engaging member.

15

The crank member 353 which is mounted on a shaft 354 has an ear 355 extending across the path of the bar 338 and adapted to be engaged by the engaging end 352 of the bar 338. Carried on the shaft 354, not shown, is a mercury switch such as that shown in copending application Serial No. 65,590, filed December 16, 1948, which when rocked connects an electric motor such as that shown in said copending application and thereby effects, through the medium of a one revolution clutch, the rotation of a shaft 356 upon which is secured a disc 357 carrying a stud 358. The stud 358 is parallel to the shaft 356 and has journaled thereon a bearing hole which is formed in one end of a curved connecting rod 360. The end of this connecting rod is retained on the stud 358 by means of a spring clip 359. The other end of the connecting rod 360 has a bearing hole formed in it which is journaled on a stud 361 which is carried on a dog 362. The dog 362 has a hub 363 which is keyed on the shaft 260. Formed integral with the dog 362 is a tab 364 which extends forwardly, as seen in Figure 13, and normally in contact with this tab is a lever 365 which has one end journaled on a stud 366, which is carried on a member 367, which is journaled on and freely movable on the shaft 269. The member 367 has a tab 368 thereon to which one end of a spring 369 is connected. The other end of the spring is connected to the stud 334 and thus the member 367 is urged by this spring in a counterclockwise direction, as seen in Figure 13. The member 367 has a downwardly projecting ear 370 which bears against the right hand edge of the lever 365 and, due to the urge of the spring 369, urges the left edge of the lever 365 against the tab 364.

The member 367 has a depending arm 371 which carries a forwardly projecting ear 372. The right edge of the arm 371, as seen in Figure 13, has a curved depression 373 formed therein which cooperates with the post 334 in a manner to be presently described.

The angular end 345 of the crank 344 is normally in contact with the surface 374 of the member 367.

The lever 365 has an elongated slot 375 formed therein adjacent to the upper end thereof, and forming a working fit in this slot is a stud 376 having an enlarged head 377. The stud 376 is secured to a bar 378 the left end of which forms a working fit in a slot formed in an annular bracket 379. The other end of the bar 378 is reciprocally carried in an elongated slot 380 formed in a lug 381 supported on the frame of the mechanism. The slot 380 is substantially longer than the width of the bar 378 so that it not only reciprocates therein but also moves laterally (up and down, as seen in Figure 13). A spring 382 has one end extending through a small hole 383 formed in the right end of the bar 378 and the other end of this spring is connected to a lug 384 which is fixed on the frame of the machine. The bar 378 has a depending extension 385 with a laterally extending tab 386 formed integral therewith.

When a push button, such as the push button 278, for example, is depressed, the screw 329, as pointed out before herein, engages the extension 328 of the member 327 which embraces the shaft 326 and thereby causes the shaft to rotate through an arc in a counterclockwise direction. The bell crank 330 moves therewith, since it is keyed to the shaft 326 and the bar 338 is moved lengthwise and it causes the shaft 354 carrying

16

a mercury switch (not shown) to rock to a position where the mercury switch is closed, thereby supplying power to the electric motor. The shaft 356 is rotated, through suitable gearing and a one revolution clutch, a single revolution in a counterclockwise direction, as viewed in Figure 13, thereby through the medium of the connecting rod 360 causing the dog 362 to move counterclockwise through an arc and return to its normal position, and thus the shaft 260 is rocked to effect the delivery of an article in the manner described in connection with Figures 11 and 12.

As the dog 362 starts moving in a counterclockwise direction the member 367 and the lever 365 move therewith until the depressed surface 373 on the member 367 comes in contact with the post 334 and from there on the member 367 is arrested. During this movement the bar 378 is moved to the left, and since the tab 386 is angularly disposed on the bar it cams over the price bar 174, and after it passes over the price bar the right end of the bar 378 is pulled downwardly by the spring 362 so that the tab 386 and its extension 385 remain on the left side of and in contact with the price bar 174.

When the push button is depressed and released before the cycle has been completed the member 367 and the lever 365 move with the dog 362 as the latter is moving in a clockwise direction to return to its normal position, and the tab 364 acting against the lever 365 and the lever in turn acting against the lug 370 causes the member 367 to move positively, against the urge of the spring 369. The surface 374 of the member 367 engages the portion 345 of the crank 344, thereby rotating the shaft 340 in a counterclockwise direction and releasing the end 321 of the push button member 322 from the radial arm 342 on the shaft 340, thereby releasing the push button 278 and withdrawing the plunger 298 from the lock out chain and the key plate 277 from one of the slots in the price bar 174. This allows the push button to return to its normal position and consequently its screw 329 is disengaged from the extension 328 and allows the bell crank 330 and its shaft 326 to return to its normal position under the urge of the spring 333. Since by this time the price bar 174 has returned to its normal position, the tab 386 is free to return to its normal position under the urge imparted to it by the lever 365. Thus everything is reset for a subsequent operation.

Assuming that the push button is depressed and is held in by the operator the cycle starts as described above and continues to the point where the radial arm 342 releases the portion 321 of the push button member 322, but the key plate 277 is still engaged with one of the notches in the price bar 174, and also the lock out plunger 298 is in engagement with the lock out chain. In addition to this the extension 328 on the shaft 326 is held in advanced position by the screw 329 on the push button assembly; therefore the bar 338 cannot return to its normal position, so that as the member 367 is moving in a clockwise direction due to the clockwise motion of the dog 362. The tab 364 acting against the left side of the lever 365 therefore acts as a fulcrum, and since the bar 378 cannot move due to the fact that the price bar 174 has not withdrawn, the result is that the member 367 is moved a greater distance than it normally is, so that the end 372 engages and lifts the bar 338 to the upper end of its slot in the member 351 and thereby its engaging end 352 is held out of the range of the tab 355 and the

mercury switch on the other end of the shaft 354 cannot be actuated.

These elements remain in this relation as long as the push button is held in. Now, if the absent-minded purchaser happens to think that he is holding the button in and releases it, the plunger 298 is withdrawn from the lock out chain and at the same time the key plate 277 is withdrawn from its notch formed in the price bar 174 and, therefore the price bar can return to its normal position and in doing so its end clears the tab 386, allowing the bar 378 to move to the right to its normal position, and in so doing the member 367 through the medium of the lever 365, its slot, and the stud 376 therein allows the member 367 to return to its normal position, allowing the bar 338 to return to its normal position within the slot in the member 351. Since the release of the push button allows the screw 329 to become disengaged with the extension 328, it and its shaft 326 together with the bell crank 330 are allowed to return to their normal position and therefore the engaging member of the bar 338 is withdrawn to its normal position with the engaging end 352 spaced apart from the tab 355 on the crank member 353 and thereafter the machine may be operated by inserting coins therein in the usual manner.

It will be evident that if the push button had been held in and anybody attempted to push in any other buttons they would be prevented from doing so because the lock out chain is filled by the plunger 298 and therefore no other plunger can enter it. It would also be prevented from operating because the bell crank 330 had not returned to its normal position to re-engage the tab 355 on the crank 353, and due to the additional fact that the left end of the bar 338 is raised so that its engaging end 352 is out of the range of the tab 355 on the crank 353 and therefore it is impossible to operate the machine by holding one of the push buttons depressed and attempting to operate another while so holding the first one.

The above description, while it has no direct bearing on the coin controlled devices per se, is explained in view of the fact that it does directly affect the price bar, the movement of which is controlled by the coin controlled devices.

It will be noted that all of the elements of the coin controlled devices are formed of stampings which can be made on a plunger press and of studs which may be produced in large quantities very cheaply on screw machines, and since dies for punching out these elements can be made very accurately, the result is the production of precision coin controlled devices in great quantities and at low cost.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope of the following claims beyond the requirements of the prior art.

What is claimed is:

1. In a vending machine, a device for setting up credits including, a price bar adapted to be moved along a fixed path in steps, a pair of coin mechanisms each adapted to be actuated by coins of a plurality of values singly, plurally or combinationally, each of said mechanisms including separate individual levers extending into coin chutes for the coins of each different value, whereby said levers are moved by the impacts of the coins passing down said chutes, and each having a positionable member conjointly controlled by its mechanism and movable in steps in accordance with the total value of the coin or coins inserted in each mechanism, rack means connected to one of said positionable members, a second rack means connected to the other of said positionable members, both said rack means being disposed in spaced parallel relation with the teeth facing each other, pinion means meshing with said rack means, and linkages between said pinion means and said price bar for causing the latter to move along said path the sum of the movements of said positionable members.
2. In a device for setting up credits, a price bar adapted to be moved along a fixed path in steps, a pair of coin mechanisms each adapted to be actuated by coins of a plurality of values singly, plurally or combinationally, each of said mechanisms including separate instrumentalities comprising individual levers and individual coin chutes for the coins of each different value, each of said levers extending into its corresponding chute, whereby said levers are moved by the impacts of the coins passing down said chutes, and each of said coin mechanisms having a positionable member conjointly controlled by its instrumentalities and movable in steps in accordance with the total value of the coin or coins inserted in each mechanism, said pair of coin mechanisms being disposed on a support in spaced parallel relation to each other, rack means connected to one of said positionable members, a second rack means connected to the other of said positionable members, channel means forming a support for both said rack means, whereby the latter are slidably movable therein with the teeth facing each other, weight means also slidably carried in said channel means, and carrying a shaft extending between said rack means, pinion means journaled on said shaft and meshed with said rack means, and linkages between said shaft and said price bar for causing the latter to move along said path the sum of the movements of said positionable members.
3. A device according to claim 2, in which the linkages between said shaft and said price bar include yieldable means.
4. A device according to claim 2, in which said weight means, through the medium of said pinion and both said rack means connected to said positionable members, tend to urge the latter in a predetermined direction and in which individual escapement means for each of said levers meters the movements of said positionable members and thereby defines said steps.
5. The invention according to claim 2, in which the coins passing through said coin chutes are all deposited in a tiltable receptacle which in normal operation is tilted in one direction to deliver the coins into a coin box, a coin return mechanism connected to said receptacle and adapted when actuated to tilt said receptacle in the opposite direction to deliver coins outside said machine, said coin return means including an element adapted to engage and raise said weight

means and thereby reset both said coin mechanisms.

6. The invention according to claim 2, in which each of said levers has an individual linearly movable escapement means cooperating therewith, in which said weight means has an engageable extension, and in which yieldable means is included in the linkages between said shaft and said price bar, resetting means being provided for engaging said engageable extension to raise said weight to a position beyond its normal position, thereby enabling said positionable members, all said levers and said escapement means to reset, said weight means being adapted to return to its normal position as the resetting means is released. 15

7. The invention according to claim 2, in which the linkages between said shaft and said price bar include, a lever having an elongated slot formed therein which rides said shaft, a clip engaging a groove adjacent to the end of said shaft, and spring means connected to said clip and to

said lever at a point spaced apart from said shaft, thereby urging the lower end of said slot against said shaft and providing yieldable means in said linkages.

5 8. The invention according to claim 7, in which said lever means is pivotally connected to crank means, and in which said crank means includes a radial slot engaging a stud in said price bar, whereby movement of said shaft in one plane is 10 imparted to said price bar in another plane.
